UNITED STATES PATENT OFFICE.

WILLIAM H. H. DANSBERRY, OF NORTH LA CROSSE, WISCONSIN.

AUTOMATIC TRAIN-STOP.

1,318,482.

Specification of Letters Patent.

Patented Oct. 14, 1919.

Application filed March 15, 1919. Serial No. 282,853.

To all whom it may concern:

Be it known that I, WILLIAM H. H. DANSBERRY, a citizen of the United States, residing at North La Crosse, in the county of 5 La Crosse and State of Wisconsin, have invented certain new and useful Improvements in Automatic Train-Stops, of which the following is a specification, reference being had to the accompanying drawings.

10 This invention relates to train stopping mechanism, and particularly to that character of train stop wherein a stop actuating track member is adapted to be shifted by a tower man or in connection with a signal 15 into or out of operative position to engage a stopping device mounted upon the forward truck of the locomotive.

The general object of this invention is to provide a construction of this character 20 wherein means are provided for automatically closing a throttle valve of the engine when the locomotive moves past a stop actuating device on the track.

A further object is to provide a construction of this character in which a locomotive throttle is closed to thereby cut off steam to the engine, and in which at the same time a vent valve in the air brake line pipe is opened to thereby cause the setting of the 30 brakes.

A further object is to provide a device of this character which, after it has been actuated, requires that the engineer must leave his cab in order to reset the parts to their 35 normal positions.

A further object is to provide a construction of this character wherein a rotatable throttle valve is provided having a stem and an arm, the valve being urged to a 40 closed position, but being held open by a latch, mechanism being provided whereby, when the track stop actuating mechanism is set, the latch will be released to permit the arm to rotate to close the throttle valve, 45 and in this connection to provide a vent valve in the train line which is struck by the rotating arm and forced to an open position.

Other objects will appear in the course 50 of the following description.

My invention is illustrated in the accompanying drawings, wherein:—

Figure 1 is a side elevation of a locomotive with my stopping mechanism applied thereto, the shell or the boiler of the locomotive being partly broken away;

Fig. 2 is a front elevation partly in section;

Fig. 3 is a sectional view of the boiler showing a throttle valve actuating mechanism;

60

Fig. 4 is a top plan view of the construction shown in Fig. 3;

Fig. 5 is a sectional view of the vent valve; and

Fig. 6 is a fragmentary sectional view 65 of the valve casing and the throttle valve.

Referring to these drawings, it will be seen that I provide in the main steam pipe 10 of a locomotive A an auxiliary throttle valve 11 which is in addition to the main 70 throttle valve 12 which is operated by means of the usual handle 13 or lever mounted within the cab. This valve 11 may be of any suitable character, but I have shown it as a rotatable valve urged to its closed 75 position by means of a spring 14 surrounding the valve stem 15, this valve stem being provided with a radially projecting arm 16.

Mounted upon the locomotive in any suitable position and coacting with this arm 80 16 is a vertically movable detent 17 which is illustrated as moving through a perforation in a bracket 18. This detent, when raised, holds the arm 16 from rotation under the action of the spring 14 and, therefore, 85 holds the valve 11 in an open position. When, however, this detent or pin 17 is withdrawn from its engagement with the arm 16, the spring will act to rotate the stem 15 and close the valve.

Coacting with the detent 17 is a bell crank 19, to one arm of which the detent 17 is connected, which bell crank is connected by a link 20 to a bell crank lever 21 mounted upon the boiler shell and in turn connected 95 to a bell crank lever 21' connected by a rod 22' to a bell crank 22, in turn connected to a vertically extending rod 23 which may be mounted to move through any suitable guide and is connected to a lever 24 whose forward 100 end is connected by a link 26 to a lever 25 fulcrumed upon a bracket 27, this lever 25 having a relatively broad and flat rear end and this lever normally extends downward and rearward so that the rear end of the 105 lever is relatively close to the track bed.

It will now be obvious that if there is anything projecting above the level of the track or in the path of movement of this actuating lever 25, it will strike this lever and through the series of links and bell crank levers raise the detent or latch 17, releasing 110

the valve arm 16, and the auxiliary throttle valve will be closed by the spring 13, thus cutting off steam supply to the locomotive cylinders.

5 I do not wish to be limited to any particular means for actuating the lever 25, but I have illustrated for this purpose a vertically shiftable actuating member 28, that is an actuating element which is shiftable in a 10 vertical plane. This is shown as a lever normally disposed below the level of the track or rail and mounted in a suitable housing 29 and connected by a rod 30 to a signal switch or to any other suitable actuating means (not shown). This rod or cable 30 might be connected to a switch tower or form part of a switch signal system or block system of a railroad so that the actuating member 28 will be shifted to its operative 15 position whenever the signal is set at "Danger" or whenever it is necessary or advisable that the train be stopped. It is obvious, therefore, that when it is desired to stop the train, this member 28 is raised and when 20 the train arrives at this point, the throttle valve will be closed.

In addition to closing the throttle, I provide means for applying the air brakes of the train to bring it to a quick stop, and to 30 this end I provide a vent valve 31 disposed in a pipe 33 connected to the train line pipe of the locomotive and having a stem 32 which projects out beyond the valve casing of the valve 31. This valve is normally 35 urged to its seat by a spring 34, but the stem 32 is so positioned that when the arm 16 is released to close the throttle valve 11, the end of the arm will strike the stem 32, forcing it inward and opening the vent valve. 40 It will be obvious that the brakes will remain applied and the throttle valve closed until the engineer leaves his cab and re-sets the valve arm 16 and the pin or detent 17. Because of the inconvenience of having to 45 do this, the engineer will be more liable to watch out for the signals and not pass a stop signal. Furthermore, it is obvious that the train will be brought to a stop even if the engineer does not see the signal, so that 50 there is no danger of the train running past a stop signal in a fog or heavy snow. Thus my device will very greatly reduce the danger of accidents.

While I have illustrated an embodiment 55 of my invention which I believe to be particularly effective, it is to be understood that many changes might be made in the details of construction and arrangement of parts without departing from the spirit of 60 the invention.

I claim:

1. In a train stop system, the combination with a locomotive having a steam pipe, a 65 throttle valve therein urged to a closed position, an air brake pipe line and a nor-

mally closed vent valve, of a detent normally holding the throttle valve open, an actuating member for said detent mounted upon the locomotive, and a stop member mounted upon the track and manually 70 shiftable from an inoperative position to an operative position where it will strike said actuating member to cause the release of said detent and the closing of the throttle valve, the movement of the throttle valve 75 to its closed position automatically opening the vent pipe valve.

2. In a train stop system, the combination with a locomotive having a steam supply pipe, a normally open throttle valve controlling the passage of steam thereto and urged to a closed position, and a detent normally holding the throttle valve open, of a vent pipe connected to the train line, of an air brake and a vent valve therein normally urged to a closed position, the throttle valve carrying a member shiftable therewith and engageable with the vent valve whereby the movement of the throttle valve to a closed position operatively engages the vent 90 valve to open it.

3. The combination with a locomotive having a steam supply pipe and having an air brake train line, of a rotatable throttle valve in the steam pipe urged to a closed position, 95 said valve having a stem and an arm, a detent holding said arm from rotation to close the valve, the vent valve being operatively connected to the train line and with which said arm engages when the throttle valve is 100 shifted to its closed position, and means arranged on the track and shiftable into or out of operative position but which, when in operative position, operatively engages the detent to shift it to release the throttle 105 valve.

4. The combination with a locomotive having a steam pipe and having an air brake train line, of a rotatable throttle valve disposed in the steam pipe and having a stem, 110 a spring urging the stem in a direction to close the throttle valve, an arm on the stem, a longitudinally shiftable detent normally engaging said arm and preventing the rotation of the valve to its closed position, and actuating devices mounted upon the locomotive adjacent the track and operatively engaged to said detent and adapted to be engaged by a movable stop device on the track when the latter is shifted into operative position, and a vent valve in the vent pipe normally urged to a closed position but struck by said arm when it is released and thereby shifted to an open position.

5. The combination with a locomotive 125 having a steam pipe, a rotatable throttle valve therein having a stem, the throttle valve extending out from the boiler of the locomotive and having an arm, a spring urging the throttle valve to its closed 130

position a vertically movable detent normally engaging said arm to prevent a movement of the throttle valve to its closed position but shiftable out of such engagement, means for releasing said detent comprising a plurality of levers and connecting links mounted upon the exterior of the locomotive and extending downward through the tracks thereof, and a lever mounted upon the locomotive adjacent the track and adapted to be struck by an ob-

struction to thereby shift the detent to its releasing position, said actuating lever being operatively connected by said links and levers to the detent.

15

In testimony whereof I hereunto affix my signature in the presence of two witnesses.

WILLIAM H. H. DANSBERRY.
